UNITED STATES PATENT OFFICE.

LERoy B. TAYLOR, OF CLEVELAND, OHIO, ASSIGNOR OF ONE-HALF TO CHRISTIAN H. JANSEN, OF EAST CLEVELAND, OHIO.

EXTRUSION PRESS.

Application filed December 8, 1927. Serial No. 238,570.

This invention relates to apparatus for extruding rods, mouldings and the like from heated billets of metal or from other plastic substances such as terra-cotta.

5 One purpose of this invention is to provide a means of producing embossed ornamentation upon the material being extruded while it is in a plastic state, that is before it has emerged from the die and started to 10 set.

A further object of this invention is to control the production of the embossed ornamentation so that the distance between successive recurring patterns will be uniform.

15 Another object of the invention is to provide improved means for supporting the product after it leaves the die, until it hardens.

20 Other objects will be made apparent in the following detail description taken in connection with the accompanying drawings forming a part of this specification, in which drawings: Fig. 1 is a plan view of one form of extrusion press equipped with the features forming the subject of this invention; Fig. 2 is a side elevation of the press shown in Fig. 1; Fig. 3 is an end elevation of the same; Fig. 4 is an enlarged section on line 4—4 of Fig. 1; Fig. 5 is a section on line 5—5 25 of Fig. 4; Fig. 6 is a partial section similar to Fig. 4 showing a modification; Fig. 7 is a section on line 7—7 of Fig. 6 and Fig. 8 is a section on line 8—8 of Fig. 4.

30 In the type of press shown horizontal tie rods 1 pass through and maintain in fixed relation a main cylinder casting 2 and a thrust block 3. The main piston 4 which works in the cylinder carries the pusher plug 5 which enters the billet receiving chamber 6, best shown in Fig. 4, and forces the material to be extruded through the channel 7 in the dies. It may be stated that the proportions of said channel 7 will be dependent on the material to be extruded.

35 The die 8 is held in a die block 40 which rests against the thrust block 3, and may conveniently be constructed of several sections 9 for ease in machining and to allow the placing of an ornamental wheel die 10 which is 40 secured to a shaft 11 which shaft projects through the die block to the outside thereof on one or both sides and is conveniently mounted in adjustably located bearings 12

whereby variation may be had for different dies that may be used interchangeably in the 55 machine.

It will be seen that the ornamental wheel die 10 is thus located at the final point of formation of the material to be extruded while it is yet plastic and not after solidification has commenced as is the case when an attempt is made to ornament the product after it has left the die.

Furthermore by locating the ornamental wheel die 10 within the body of the die 8 the material being extruded is necessarily held by the remainder of the die sections 9 so that there can be no distortion due to the impression of the ornamental wheel die 10.

This channel 13 through which the material 70 passes after leaving the ornamental die wheel 10 may provide for clearance for the product or not, depending on the material being extruded.

A buffer plate 14 with clearance for the 75 product is conveniently provided between the die and the thrust block 3 to reinforce die 8 and billet receiving chamber 6.

The rotation of the ornamental wheel die 10 is controlled by means actuated by the extruded product itself. In order to commence this action as soon as the first of the product is formed, a bar 15 having one end 16 of about the same section as the opening in the die is inserted in channel 13 to about the 80 center of the ornamental wheel die 10. When the extruded product starts, it forces the bar 15 in a rearward direction and by means such as a yoke or arm 17 secured to the bar 15 and said yoke 17 having pins 18 secured 90 thereto adapted to fit into chains 19 which in turn operate sprockets 20 and the shaft 11 on which said sprockets 20 are mounted, the ornamental wheel die 10, also mounted on said shaft 11 is caused to rotate. It will be noted 95 that the pitch diameter of the sprockets 20 should be the same as the outside diameter of ornamental wheel die 10. The chains 19 are maintained in working position by adjustably mounted idler sprockets 21 supported 100 by standards indicated as a whole at 41.

To prevent the product from becoming dislocated from the end of bar 15 after emerging from the channel 13 and buffer plate 14, a sleeve 22 having a cupped end 23 surrounds the bar 15. Said sleeve 22 is main-

tained in contact with buffer plate 14 by means of a detent 24 mounted on said sleeve 22, engaging with a stop 25 attached to the thrust block 3 of the press.

- 5 The bar 15 is further provided with means such as a ratchet 26 coacting with a pawl 27 and spring 28, mounted in above mentioned sleeve 22 which means maintain the engagement of the detent 24 and stop 25 above mentioned until the end of the product has entered within the cupped end 23 of the sleeve 22, at which time the sleeve 22 is forced by a spring 29 so as to disengage the detent 22, whereupon the sleeve 22 travels with the 10 bar 15 maintaining the alignment of the product with the bar 15 by means of the surrounding cup 23.

A pan 30 may conveniently be mounted so as to provide a coolant or other solidifier 20 for the product as it emerges from the machine.

A modification is shown in Figs. 6 and 7 in that a mating wheel die 31 is installed on the opposite side of the product from 25 that occupied by the ornamental wheel die 10. By this construction a uniform thickness of product may be maintained although the product have an embossed pattern thereon. Although only one pair of mating die wheels 30 are shown it is understood that any number might be used.

In Fig. 7 the die wheel shafts 32 and 33, mounted in bearings 34 are shown provided with gears 35 and 36 meshing with a drive gear 37 which may be driven by a chain as before described or by any adjustable speed drive indicated in general by sprocket wheel 38.

It is also within the scope of this invention that the mating wheel die 31 might be replaced by an unembossed wheel if desired to aid in the travel of the product through the machine, especially in the case of a very hard product, even though it be 45 not required that the reverse side of the product be given a different outline than that given it by the non-rotating portion of the die.

In operation the billet or material to be extruded is placed in the chamber 6 and the ram 5 is then advanced into the chamber by the piston 4 operated by any kind of fluid pressure. This forces the material through the die, and as it passes the design 55 is impressed thereon by rotation of the wheel 10. As the product leaves the die it is received by the cup 23 and sleeve 22 and passes therewith into the cooling pan 30 from which it may be removed in any suitable way.

I claim:

1. The combination in an extrusion press, of a die including a rotary member, a shaft on which said member is mounted, a rod located in line with the outlet from the die and adapted to be moved by the product 65 as it is discharged from the die, and driving connections between the rod and the shaft.
2. The combination stated in claim 1, said driving connections including a sprocket 70 chain operatively connected to the shaft and a projection carried by the rod and engageable with said chain.
3. In an extrusion press the combination of a thrust block having an opening, a die 75 resting against the thrust block with its outlet in line with said opening and provided with a wheel member for ornamenting the product, a rod working in said opening, and having a cupped sleeve at its inner end to receive the product after it passes the die, and driving connections between the rod and the wheel member.
4. The combination stated in claim 3, the sleeve being adjustably mounted on the rod. 85
5. The combination stated in claim 3, the sleeve having a pawl and ratchet connection to the rod.
6. The combination stated in claim 3, the sleeve being adjustable on the rod, and a releaseable stop engaging the sleeve to hold it in initial position.
7. The combination stated in claim 3, the die block having a stop, and the sleeve having a projection engageable with said stop 95 in initial position and disengageable therefrom after the rod is moved to a certain extent.
8. In an extrusion press, the combination of a thrust block having an opening, a die 100 resting against said thrust block with its outlet in line with said opening, and including a wheel member to ornament the product, a shaft on which the wheel member is mounted, a sprocket chain operatively connected to the shaft, a rod located in said opening and movable by contact of the product as it leaves the die, and an arm attached to the rod and engageable with the chain to drive the same and the shaft as the product 105 is delivered from the die.
9. The combination stated in claim 8, and a slidabile support for the rod adapted to move therewith after a certain amount of product has been delivered.

In testimony whereof, I do affix my signature.

LEROY B. TAYLOR.
